UNITED STATES PATENT OFFICE.

EDMUND D. KILMARTIN, OF ADA, MICHIGAN.

ENSILAGE PACKER.

Application filed June 18, 1921. Serial No. 478,714.

To all whom it may concern:

Be it known that I, EDMUND D. KILMARTIN, a citizen of the United States, residing at Ada, in the county of Kent and State of Michigan, have invented new and useful Improvements in Ensilage Packers, of which the following is a specification.

This invention relates to devices used in connection with silos and has for its object 10 the provision of a motor driven packing means for pressing down ensilage deposited within the silo whereby the ensilage will be properly compressed and the capacity of the silo consequently increased, the device 15 being more rapid and efficient in action than the usual method of packing which consists in the trampling down of the ensilage by workmen.

An important and more specific object is 20 the provision of a device of this character which may be clamped upon a silo of any dimensions and which includes a motor driven packer which is rotated continually so as to engage all portions of the top surface 25 of the mass of ensilage as it is deposited within the silo so that the packing will be uniform.

An additional object is the provision of a 30 device of this character which will be simple and inexpensive in manufacture, easy to install, highly efficient in use, durable in service, and a general improvement in the art.

With the above and other objects and advantages in view, the invention consists in 35 the details of construction to be hereinafter more fully described and claimed and illustrated in the accompanying drawings in which—

Figure 1 is a plan view of my device associated with a silo,

Figure 2 is a side elevation of my device, the silo being in section,

Figure 3 is an enlarged longitudinal sectional view through the central portion of 45 my device,

Figure 4 is a detail sectional view illustrating the adjustable arms clamped upon the silo,

Figure 5 is a detail view of the rope taking up means.

Referring more particularly to the drawings, the letter A designates a silo upon which my device is secured. In carrying out my invention I provide a spider-like bearing member 10 formed centrally with a hole 11 and likewise formed with upstanding ears

12 provided with bearings 13. This bearing member 10 includes a plurality of radial arms 14 with which are slidably adjustably connected rods 15 having angular downturned ends 16 engageable over the upper edge of the silo. These ends 16 are preferably formed with eyes 17 for the attachment of guy wires 18 or the like whereby to steady the device and in fact to steady the whole 60 silo while the filling thereof is being accomplished.

Journaled through the bearings 13 is a horizontally disposed shaft 19 provided at one end with a suitable pulley 20 about 70 which may be engaged a suitable belt, not shown, driven by any suitable portable gasoline engine, electric motor, or other power device. Associated with the pulley 20 is a guide 21 for the purpose of holding the belt 75 associated therewith against displacement. Between the ears 12 the shaft 19 carries a relatively small bevel gear 22 and a larger gear 23.

Journaled through the hole 11 in the bearing member 10 is a vertically disposed shaft 24 which is provided at its upper end with a bevel gear 25 meshing with the gear 22 and at the lower end of the shaft 24 is a bevel gear 26. Surrounding and rotatable 80 upon the shaft 24 is a sleeve 27 which has its upper end provided with a gear 28 meshing with the gear 23. Secured to the lower end of the sleeve 27 is a horizontal sleeve 29 which is additionally connected with the 85 sleeve 27 by an inclined brace 30. Journaled through the sleeve 29 is a shaft 31 which is provided at one end with a bevel gear 32 meshing with the gear 26 and which is provided at its other end with a crank 33 to 90 which is connected a rope or other flexible member 34 with which is connected a suitable take up device 35 of conventional pattern. Carried by this rope 34 is a bar 36 which is formed quite heavy and which is 100 designed to engage and tamp down the ensilage within the silo. This bar is formed with a series of holes 37 within selected ones of which may be engaged the rope, it being preferable that two points of connection be 105 used.

The operation of the device is as follows:

Assuming that the shaft 19 is rotating through the instrumentality of any suitable power device and assuming that ensilage is 110 being deposited within the silo by any means, the engagement of the gear 23 with the gear

28 will cause rotation of the sleeve 27 and consequently movement of the horizontal sleeve 29 within the silo. At the same time, the gear 22 meshing with the gear 25 will 5 cause rotation of the shaft 24 and consequent rotation of the shaft 31. As the shaft 31 is rotated the crank 33 thereon will pull the bar 36 up and then allow it to descend and this will naturally result in packing down 10 the ensilage. Owing to the fact that the sleeve 29 carrying this crank shaft is rotated it is apparent that the bar will engage and tamp down all portions of the ensilage so that uniform packing and compression will 15 result. As the depth of the ensilage increases it is quite apparent that the rope or other flexible device 34 must necessarily be shortened and this is easily accomplished by means of the take up device 35 while the 20 device is in operation, it being entirely unnecessary to cause a cessation of the packing action to accomplish this minor adjustment.

From the foregoing description and a 25 study of the drawings it will be apparent that I have thus provided a simply constructed and consequently inexpensive device which is adjustable for engagement upon any silo and which is so constructed that 30 it will efficiently and uniformly pack or tamp down ensilage in a highly efficient manner and much more easily and more economically than this same work can be accomplished by workmen trampling down the 35 ensilage with their feet.

While I have shown and described the preferred embodiment of my invention, it is of course to be understood that I reserve the right to make such changes in the form, 40 construction and arrangement of parts as will not depart from the spirit of the invention or the scope of the subjoined claims.

Having thus described my invention, I 45 claim:

1. A device of the character described comprising a bearing device adapted to be secured upon the top of a silo, a member journaled with respect to said bearing member and rotatable within the silo, means for 50 driving said member to effect rotation thereof, a horizontal shaft journaled within said member and formed with a crank, means for driving said shaft simultaneously with the rotation of said member, an adjustable 55 flexible member connected with said crank, and a tamping member carried by said flexible member.

2. A device of the character described

comprising a bearing spider adapted to be secured upon the upper edge of a silo, a vertical shaft journaled through said bearing member, means for rotating said shaft, a sleeve surrounding and rotatable with respect to said shaft, means for rotating said sleeve, a horizontal sleeve rigidly secured to said first named sleeve, a horizontal shaft journaled through said horizontal sleeve and driven by said first named shaft, a crank on said last named shaft, an adjustable flexible member connected with said 60 crank, and a weight member carried by said flexible member.

3. A device of the character described comprising a bearing spider adapted to be secured upon the upper edge of a silo, a vertical shaft journaled through said bearing member, means for rotating said shaft, a sleeve surrounding and rotatable with respect to said shaft, means for rotating said sleeve, a horizontal sleeve rigidly secured to 65 said first named sleeve, a horizontal shaft journaled through said horizontal sleeve and driven by said first named shaft, a crank on said last named shaft, an adjustable flexible member connected with said 70 crank, and a heavy bar carried by said flexible member, the means for driving said first named shaft and first named sleeve comprising a horizontal driven shaft journally associated with said bearing, a pair of gears 75 on said last named shaft, and gears on the upper ends of said first named shaft and said first named sleeve meshing with said pair of gears.

4. A device of the character described comprising a bearing spider adapted to be secured upon the upper edge of a silo, a vertical shaft journaled through said bearing member, means for rotating said shaft, a sleeve surrounding and rotatable with respect to said shaft, means for rotating said sleeve, a horizontal sleeve rigidly secured to 80 said first named sleeve, a horizontal shaft journaled through said horizontal sleeve and driven by said first named shaft, a crank on said last named shaft, an adjustable flexible member connected with said 85 crank, and a heavy bar carried by said flexible member, said bearing member including a stationary central portion having radial rigid arms and further including rods slidably 90 adjustably connected with said arms and having forked ends engageable over the edge of the silo.

In testimony whereof I affix my signature.
EDMUND D. KILMARTIN.
